DESIGN FOR A COMBINED FRAME AND HANDLE FOR FISH NETS

James W. Harvey, Lakeville, Conn.

Application October 15, 1946, Serial No. 133,956

Term of patent 7 years

(Cl. D31—4)

To all whom it may concern:

Be it known that I, James W. Harvey, a citizen of the United States of America, residing at Lakeville, Litchfield County, and State of Connecticut, have invented a new, original, and ornamental Design for a Combined Frame and Handle for Fish Nets, of which the following is a specification, reference being had to the accompanying drawing, forming part thereof.

Fig. 1 is a plan view of a combined frame and handle for fish nets, showing my new design.

Fig. 2 is a perspective view on a reduced scale of the design shown in Fig. 1 and showing the net for illustrative purposes only.

Fig. 3 is a fragmental detail taken at the junction between the frame and the handle.

Fig. 4 is a face view of a fragment of the junction between the frame and the handle.

Fig. 5 is a fragmental view looking in the direction of the arrows in Fig. 1.

I claim:

The ornamental design for a combined frame and handle for fish nets, substantially as shown and described.

JAMES W. HARVEY.
